UNITED STATES PATENT OFFICE.

JOSEPH MCKAY, OF TROY, NEW YORK, ASSIGNOR TO HALL, HARTWELL & CO., OF TROY, NEW YORK, A FIRM COMPOSED OF WILLIAM L. HALL, JOSEPH MCKAY, AND BURTON K. WOODWARD.

SOFT FOLD-COLLAR.

1,200,381.

Specification of Letters Patent.

Patented Oct. 3, 1916.

Application filed January 6, 1915. Serial No. 713.

To all whom it may concern:

Be it known that I, JOSEPH MCKAY, a citizen of the United States, residing at Troy, county of Rensselaer, and State of 5 New York, have invented certain new and useful Improvements in Soft Fold-Collars, of which the following is a specification.

The invention relates to such improvements and consists in the novel construction 10 and combination of parts hereinafter described and subsequently claimed.

Reference may be had to the accompanying drawings, and the reference characters marked thereon; which form a part of this 15 specification. Similar characters refer to similar parts in the several figures therein.

Figure 1 of the drawings is a plan view of a soft fold-collar embodying my invention, the collar being laid out flat and portions of the band-plies broken away for 20 convenience of illustration. Fig. 2 is a vertical cross-section of the same taken on the broken line 2—2 in Fig. 1. Fig. 3 is a horizontal cross-section of the same taken on the 25 broken line 3—3 in Fig. 1. Fig. 4 is a horizontal cross-section of the same taken on the broken line 4—4 in Fig. 1. Fig. 5 is a view in perspective of one of the band-stiffening strips adapted for use as illustrated in 30 Fig. 4.

The principal object of the invention is to provide a soft fold-collar with a readily laundrable band having permanently contained stiffening or supporting devices for 35 holding the band upright in use.

Other objects of the invention will appear in connection with the following description.

Referring to the drawings, 1 is the top 40 and 2 is the band of a soft fold-collar of ordinary design. The band, 2, is made up of a plurality of plies, three plies being shown in the sectional views. At more or less frequent intervals the band is provided with 45 stiffeners or supporters permanently secured between the plies. These stiffeners or supporters are in the form of long narrow strips which stand upright in the band as worn; and in one form of my invention, 50 such a stiffener-strip, 3, is located between the plies of the band, as indicated by dotted lines in Fig. 1, and is wholly surrounded by stitching whereby the plies are secured together. Thus, as shown in Fig. 1, the stiff-

ener is wholly surrounded by the seam, 4, 55 whereby the top is secured in the upper edge of the band, the seam, 5, whereby the lower edges of the band-plies are secured together, and two vertical lines of stitching, 6—6, extending along the opposite sides of the 60 stiffener. I have also shown another form of stiffener-strip, 7, similarly inclosed between the band-plies, and which may also be surrounded by stitching, 4, 5, and 6, as above described. This latter form of stiffener is inclosed in a binding, 8, which extends beyond the edge of the strip on one side, the edges of the binding being secured together by stitching, 9. With this form of bound stiffener-strip, I prefer to connect the 70 strip directly to the band-plies by means of stitching, 10, inserted through the several band-plies, and the edges of the binding-strip, 8, as shown at the broken-away portion of the band adjacent to the broken line, 75 4—4 in Fig. 1.

The stiffener-strips, 3, and the core, 7, of the bound stiffener-strip may, for certain purposes of the invention, be made of any stiff resilient material such as featherbone 80 or equivalent material having stiffness and resiliency, adapted to be readily penetrated by the sewing-machine-needle, and not injuriously affected by moisture and the ordinary heat to which collars are subjected 85 in the laundrying operation. I prefer to make these stiffeners of featherbone, which I have found highly desirable for the purpose, because of the lightness of the material, and the fact that it can be readily 90 punctured by the sewing-machine-needle, so that should the operator in inserting the stitching, whereby the stiffeners are secured in position, fail to avoid the body of the stiffener, and should insert more or less of 95 the stitches through the same, it will cause no harm either to the needle or to the stiffener. The collar having such stiffeners in its band is laundried with no more difficulty than a collar having an ordinary band. The 100 stiffeners of featherbone readily withstand the heat and moisture of the laundrying operation; and when the collar is ironed and dried, they serve effectively to hold the band in upright position in use, yielding 105 readily to the movements of the wearer, yet being so resilient as to at once return to upright position when relieved of strain.

What I claim as new and desire to secure by Letters Patent is—

1. A soft fold-collar having a top, and a band composed of a plurality of plies and 5 independent stiffening strips of featherbone permanently secured between the plies of the band by stitching.
2. A soft fold-collar having a top, and a band composed of a plurality of plies, and 10 having inserted between the plies of the band a strip of featherbone inclosed in a

cloth-binding with the edges of the binding extending beyond one side of the strip of featherbone, the edges of the binding and the band-plies being secured together by 15 stitching inserted therethrough.

In testimony whereof, I have hereunto set my hand this 19 day of December, 1914.

JOSEPH McKAY.
